HOLSTER BODY

Harvey Brent Mason, 142 Loma Vista, Covina, Calif.

Filed Mar. 1, 1963, Ser. No. 73,778

Term of patent 14 years

(Cl. D30—1)

FIG. 1 is a side elevation of a holster body showing my new design; and

FIGS. 2, 3, 4 and 5 are top, bottom, left-hand and right-hand views, respectively, of FIG. 1.

I claim:

The ornamental design for a holster body, as shown.
